The ornamental design for electronic information terminal, as shown and described.

DESCRIPTION

FIG. 1 is a front view of an electronic information terminal, showing the new design.

FIG. 2 is a perspective view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a part cross-sectional view taken along line 8—8 at portion A in FIG. 1; and,

FIG. 9 is a part cross-sectional view taken along line 9—9 at portion C in FIG. 1.

The broken lines shown in the drawings represent unclaimed portions of the electronic information terminal and form no part of the claimed design.
